DESIGN FOR A LACE

Leon Birnbaum, New York, N. Y.

Application November 28, 1936, Serial No. 66,180

Term of patent 3½ years

To all whom it may concern:

Be it known that I, Leon Birnbaum, a citizen of the United States of America, residing in the city of New York, county of New York, and State of New York, have invented a new, original, and ornamental Design for a Lace, of which the following is a specification, reference being had to the accompanying drawing, forming part thereof.

The figure of the drawing is a plan view of a lace embodying my new design.

The design unit is contained between the vertical broken lines, which unit is repeated in regular succession, as indicated by the extensions beyond the unit boundaries.

I claim:

The ornamental design for a lace substantially as shown and described.

LEON BIRNBAUM.
